3,191,904 PLASMA SUPPORT UNIT

Alexander D. Karapita, % Canadian Research and Development Foundation, 1434 Queen St. W., Toronto 3, Ontario, Canada

Filed Aug. 4, 1961, Ser. No. 129,440
3 Claims. (Cl. 248—333)

This invention relates to telescopic ceiling fixtures, and more particularly to telescopic fixtures utilized for supporting containers of plasma and intravenous fluids.

It is required that such fixtures support containers of plasma and intravenous fluids in an inverted manner, thereby permitting the contents of the containers to flow downwardly by gravity to the patient.

It is conventional practice to utilize castered floor stands, which have proven to be only partially satisfactory because of their bulk and weight. Another disadvantage of the conventional floor stand is that it is sometimes knocked over resulting in the loss of the fluid being dispensed onto the floor, thereby worsening the patient's condition.

It is an object of this invention to provide a plasma support unit which may be suspended from the ceiling by a stationary hook, or a travelling hook, thereby replacing the conventional floor stand.

It is another object of this invention to provide a plasma support unit which will be telescopic, requiring the use of only one hand for the lengthening or shortening thereof.

It is another object of this invention to provide a plasma support unit which can be displaced from its vertical suspended position to an angular position, and locked in that position for the purpose of holding the assembly clear of a patient's bed and operating table.

These and other objects and features of this invention will become apparent when taken in conjunction with the following drawings in which:

FIG. 1 is a vertical elevation of the plasma support unit suspended from a ceiling and shown in its extended position.

FIG. 2 is a composite vertical elevation of the plasma support unit illustrated in FIG. 1, showing the fixture in vertical position and, in phantom, the fixture moved into an inclined position.

FIG. 3 is a vertical, part sectional elevation of the plasma support unit illustrated in FIG. 1, showing particularly the construction thereof.

FIG. 4 is a vertical, fragmentary, sectional elevation of the plasma support unit illustrated in FIG. 1.

FIG. 5 is a fractional perspective view of the upper end of the plasma support unit illustrated in FIG. 1 showing particularly an alternative method of suspending the unit, through track and carrier members, for added mobility.

The invention consists essentially in a telescopic assembly including a central rod removably suspended from a hooked ceiling support, a tube and an outer sheath concentrically mounted about the central rod and normally held in locking engagement with the central rod in any adjusted position thereon, the locking means consisting of a series of spring fingers on the end of the tube normally held in locking contact with the central rod by pressure from the sheath, and a spring grip means associated with the central rod and the sheath for effecting release of the locking contact pressure between the spring fingers of the tube and the central rod. The invention also consists of means to hold the telescopic assembly in any angular position inclined from the vertical, the said means comprising a link connected at one end to the ceiling support and at the other end to a locking sleeve slidably mounted on the sheath of the telescopic assembly.

2

Referring to the drawings, the ceiling fixture comprises an outer sheath 10 having at its bottom end a threaded portion on which is screwed a knurled nut 11 and a hollow handle 12 which is also knurled. A tube 13 is slidably mounted within the sheath 10. At its lower end the tube 13 has fastened a bushing 14 threaded to receive a stub rod 15 of restricted diameter, which extends out of the handle 12 through a hole in the bottom of the handle. A compression coil spring 16 is mounted inside the handle 12 and bears against the shoulder formed by the bushing 14.

At its upper end the sheath 10 is formed with an inwardly projecting lip 17. The tube 13 has at its upper end a plurality of circumferentially disposed fingers 18 flared inwardly at 19 at their outer extremities.

A rod 20 (which may also consist of a tube) is slidably mounted within the tube 13 and projects beyond the fingers 18 in all its positions, its retraction into the tube 13 being limited by the lower end of the rod 20 abutting the inner end of the stub rod 15.

The above described arrangement is such that the spring 16 urges the tube 13 upwardly and its fingers 18 engage with their flared portions 19 the lip 17 of the sheath 10. The fingers are thus pressed against the rod 20 and hold it in position by frictional engagement.

A lever 21 is provided to release the fingers and allow rod 20 to slide freely within the tube 13. The lever 21 has a main portion aligned with and spaced from the handle 12, and a smaller portion 22 at a right angle to the main portion. The portion 22 has a hole 23 loosely surrounding the outwardly extending portion of stub rod 15. A pin 24 traverses the stub rod and rests in a groove on the outer face of lever portion 22.

When the main portion of lever 21 is pulled towards the handle 12 (FIG. 4) the smaller portion 22 bearing against the outer edge of the bottom of the handle which acts as a fulcrum point 25, pulls the stub rod 15 downwardly against the pressure of spring 16 and with it the tube 13, and causes the finger portions 19 to become disengaged from the lip 17, so that the fingers 18 no longer press against the rod 20. In this condition the relative position of rod 20 and sheath 10 can be adjusted telescopically. Any slack in the lever 21 can be removed by turning back the handle 12 and readjusting the position of nut 11.

The sheath 10 has mounted thereon a device for hanging the containers, said device consisting of a ring 26 secured to the sheath 10 by means of a set screw 27 and having fastened thereto a pair of opposite arms 28. The arms 28 are shown in dotted lines in FIG. 3 turned 90° to the plane of the figure. At their ends the arms 28 are formed with hooks 29. The containers are hung from the hooks 29 in an upside down position by conventional means (not shown). In addition a hook 30 is screwed into the outer end of stub rod 15.

The rod 20 has at its lower end a flange 31 which engages an inwardly projecting annular rib 32 of tube 13 to prevent complete disengagement of the rod from the tube. At its upper end the rod 20 has a short transverse bar 33 which sits in a hooked tubular support 34 permanently secured to the ceiling by a screw 35. The support 34 has a suitable recess for receiving the bar 33. The face opening of the recess permits insertion of the bar 33 edgewise at an angle but is not large enough to permit removal of the bar 33 facewise, so that the bar 33 can only be removed by moving it upwardly in the recess at a certain inclination, moving it outwardly at the bottom and then downwardly. This arrangement prevents the fixture from falling off the support accidentally.

A sleeve 36, threaded intermediate its ends and provided with downwardly projecting fingers 37, wedge-shaped in longitudinal section, is slidably mounted on the sheath 10

above the ring 26. A knurled sleeve-nut 38 engages the thread of sleeve 36. The nut 38 has its lower inner wall flared inwardly to engage the fingers 37 and tighten them against the sheath 10 when the nut 38 is turned upwardly. The sleeve 36 has a bracket 39 on which is pivotally mounted one end of a link 40, the other end of which is bent and may be attached to a hook 41 secured near the upper end of support 34 on the side thereof opposite that on which opens the recess.

The fixture may swing about the lower edge of bar 33 in the plane of FIGS. 2 and 3 and can be held in an inclined position, as shown in FIG. 2, by fastening the sleeve 36 on the support 34.

As mentioned above the invention is particularly useful in hospitals for holding containers during transfusions. In practice a ceiling support 34 is mounted at every place where a transfusion may have to be made, for example above each bed in wards and above the operating table in operating rooms. Whenever a transfusion is needed a fixture is hooked to the support. When it is desired to get the fixture out of the way temporarily, for example while the patient is being prepared, the fixture may be pushed up to the ceiling. When the actual transfusion begins the fixture is then pulled down to a suitable level.

The possibility of retaining the fixture in an inclined position is of particular utility when the bed or table has to be moved about a great deal, for example in the operating room, or when the patient is being transferred from the operating table or bed to a stretcher.

Referring to FIG. 5, a track 50, of substantially elongated, tubular configuration, formed of rigid materials, such as, for instance, steel, aluminum or the like, is slotted along its lower face 51, thereby providing a running surface 52. A movable support carrier 53, is carried by a plurality of substantially friction free wheels 54, adapted to move freely along running surface 52 of track 50.

A support 55 similar in design to support 34 is attached to support carrier 53 by conventional means, for the hanging thereon of the plasma support unit, the contour of track 50 restraining any transverse or axial movement of support carrier 53.

Track 50 is adapted to be mounted by conventional fastening means by the insertion of screws or the like through a plurality of holes 56 through face 57 of track 50.

The general design of the individual parts of the invention as explained above may be varied in accordance with the requirements in regard to manufacture and produc-

tion thereof, while still remaining within the spirit and principle of the invention, without prejudicing the novelty thereof.

The embodiments of this invention in which an exclusive property or privilege is claimed are defined as follows:

5 1. A plasma support unit including a ceiling support, an outer tubular sheath having means for holding objects, an inner rod slidably mounted within said sheath and pivotally mounted at one end in said ceiling support, means providing a plurality of fingers surrounding said rod, means in said sheath engageable with said fingers and adapted to press the said fingers against said rods, means to urge said finger means and said finger engaging means longitudinally against each other to fasten together said rod and said sheath in their axially adjusted position, means to hold said ceiling fixture in said ceiling support in a variable position inclined from the vertical, said means for holding the said ceiling fixture in an inclined position comprising a sleeve slidably mounted on said sheath, said sleeve having a plurality of fingers and an outer thread, a nut mounted on said thread and engageable with said fingers to press them against said sheath and a link pivoted to said sleeve and hooked to said overhead support.

10 2. A plasma support unit as claimed in claim 1 wherein said object holding means comprises a pair of hooks, located on opposite sides of said support unit, adapted to receive transfusion containers.

15 3. A plasma support unit as claimed in claim 1 in which said ceiling support includes a tubular track member for attachment to a ceiling and having a longitudinal slot running substantially centrally through the lower face thereof, a support carrier within said track member, wheels supporting said carrier enabling said carrier to run freely longitudinally within said track member, and suspension means depending from said carrier in cooperation with said securable means at one end of said inner rod for the support of said fixture.
